UNITED STATES PATENT OFFICE

158,849

TABLE TOP OR SIMILAR ARTICLE

Charles H. Frederick, Beaver Falls, Pa., assignor to Ingram-Richardson Manufacturing Company, Beaver Falls, Pa., a corporation of Pennsylvania

Application November 6, 1947, Serial No. 142,354

Term of patent 3½ years

(Cl. D33—14)

To all whom it may concern:

Be it known that I, Charles H. Frederick, a citizen of the United States of America, residing at Beaver Falls, in the county of Beaver and State of Pennsylvania, have invented a new, original, and ornamental Design for a Table Top or Similar Article, of which the following is a specification, reference being had to the accompanying drawing, forming part thereof.

The figure is a plan view of a table top showing my new design, the ornamentation being shaded to show color.

The table top is of conventional thickness.

I claim:

The ornamental design for a table top or similar article, as shown and described.

CHARLES H. FREDERICK.
